US00D385365S

United States Patent [19]

Perrault

[11] Patent Number: Des. 385,365

[45] Date of Patent: **Oct. 21, 1997

[54] PYLON

[76] Inventor: Dominique Perrault, 26/34 rue
Bruneau, 75013 Paris, France

[**] Term: 14 Years

[21] Appl. No.: 44,426

[22] Filed: Sep. 25, 1995

[30] Foreign Application Priority Data

Mar. 23, 1995 [FR] France 951 745
